[57] CLAIM

The ornamental design for an automobile tire, as shown and described.

DESCRIPTION

FIG. 1 is a front elevational view of the automobile tire showing my new design; the top and bottom plan views and rear elevational view being identical to the front elevational view;

FIG. 2 is a right side elevational view thereof; the left elevational view being identical to the right side elevational view;

FIG. 3 is an enlarged fragmentary view of the section taken along the lines 3-3 in FIG. 1; and,

FIG. 4 is a cross sectional view taken along the line 4-4 in FIG. 3.
